UNITED STATES PATENT OFFICE

EDWIN F. M. SPEIDEL, OF EDGEWOOD, RHODE ISLAND

DESIGN FOR A BRACELET CHAIN

Application filed August 27, 1930. Serial No. 36,795. Term of patent 3½ years.

To all whom it may concern:

Be it known that I, EDWIN F. M. SPEIDEL, a citizen of the United States of America, one of the links.

residing in Edgewood, county of Providence,

I claim:

State of Rhode Island, have invented a new, original, and ornamental Design for a Bracelet Chain, of which the following is a specification, reference being had to the accompanying drawing, forming a part thereof.

The ornamental design for a bracelet chain, substantially as shown.

EDWIN F. M. SPEIDEL.
